tion, New York, N. Y., a corporation of New
York

Application May 7, 1935, Serial No. 20,128

17 Claims. (Cl. 164—115)

This invention relates to devices for perforating and checking a record of datum which is selected from one of a plurality of datum fields on a pattern record. In the illustrative machine disclosed hereinafter, the record which is perforated is in the form of a detail card in which appear special prepunched perforations that are used to control the selection of information from a plurality of fields on a pattern or extension record card. The presence and location of the special prepunched perforations in the detail card determine which of the perforated fields on the pattern is to control the perforation of the detail card. In other words, special perforations in a detail card determine which of a series of perforations in an extension card are to be read to control the perforation of the detail card.

The devices of the present invention are an improvement in the reproducing punch machine disclosed in application Serial No. 685,379, filed August 9, 1933, by C. D. Lake, now Patent 2,032,805, granted March 3rd, 1936.

An object of the invention is the provision of devices for perforating a record under control of a selected portion of a pattern; the selection of the portion being controlled by the record to be perforated.

Another object of the invention is the provision of perforating devices which are operated under the joint control of a detail card and pattern card.

A feature of the present invention is the arrangement of perforating control devices under the influence of a combination of special perforations in a detail card to select one of a plurality of fields of perforated data on a pattern card to control perforating operation.

It is also an object of the invention to provide devices for checking the selected perforations on the detail card with a certain field of perforations on the pattern, which field was originally selected to control perforation. Sensing devices read and compare the perforations on the detail and pattern cards. An indication of disagreement is given by lighting a lamp and stopping the perforating devices when the selected perforated data on the two cards fail to coincide.

Another object of the present invention is the provision of means for causing selective reproduction of data perforated in a pattern.

Another object of the invention is the provision of class selection devices which are controlled by special perforations in the detail card which is to be punched with the class selected data.

The foregoing and other objects of this in-

vention will be apparent as this specification continues with reference to a set of drawings which forms part of the present disclosure.

Fig. 1 is a sectional elevation view taken through the center of the card sensing and perforating devices.

Fig. 2 is a view of a sample detail card.

Fig. 3 is a detail view of an extension or pattern card associated with the card in Fig. 2.

Figs. 4A and 4B together form a wiring diagram of the machine.

Figs. 2 and 3 show examples of record cards used to control the reproducing devices of the present invention. In Fig. 2 there is illustrated a detail card, a portion of which is perforated before the card is inserted in the reproducer. This prepunched section of the card is identified by bracket A, including the fields devoted to name, address, date, base rate, and meter readings. The remaining fields of the card included in bracket B are perforated under control of the extension card shown in Fig. 3. The perforation of card 11 is selective in that one of a plurality of fields on the extension card is selected to control the perforation in the detail card. The selection is accomplished under control of two special perforations x and z perforated in the prepunched section of the detail card. The presence of either one of these two special holes or the absence of both, determines the selection of one of three fields of prepunched data on the extension card for use in controlling reproduction thereof in the detail card.

A general idea of the mode of operation of the reproducing devices of the present invention may be gathered by noting the handling of the cards 10 and 11 in a sectional view shown in Fig. 1. There it is noted that a number of extension cards 10 are placed in hopper R and another group of related detail record cards 11 are assembled in hopper P. Each card in the one hopper has a related card in the other hopper, the card 10 controlling the perforation of the card 11. The cards are fed to the right, singly but concurrently from both hoppers. They are then shifted in synchronism across sensing and punching stations before being deposited in stackers 12 and 13.

The extension card 10 encounters first a master sensing brush 14, then a set of sensing brushes 15 and finally a series of checking brushes 16 before being thrown into the stacker 12. The detail card 11 passes a pair of class selection master brushes 17x and 17z which sense the special perforations x and z pointed out in Fig. 2. Then

the detail card passes a line of punches after which the perforations are sensed by a set of checking brushes 19 before the card is dropped into the stacker 13.

5. Electrical connections may be made between the brushes 15 and punches 18 so that when a perforation is sensed in an extension card 10 a corresponding perforation is punched in the related detail card 11.

10. The special brushes 17x and 17z and class selection magnets connected thereto control the operations of the devices of the present invention. They serve to connect certain of the punches 18 with one of three fields of brushes 15.

15. They also control the selective connection of certain of the checking brushes 19 to one of three sections of similar sensing brushes 16 cooperating with the extension card 10. The purpose of such class selection is to pick one of a plurality of fields 20 on the extension card 10 and thereby control the punching of the detail card, and after the punching is completed, to check the punching with the original perforations in the extension card.

25. As two related extension and detail cards pass the first sensing and punching stations, they enter the checking sensing stations including brushes 16 and 19.

The extension card 10 is sensed by checking brushes 16 at the same time that the related 30 detail card 11 is sensed by checking brushes 19. If the reproduced perforations in both do not agree, the machine is stopped and a lamp lights to indicate the error to the operator.

35. The invention is illustrated in connection with a problem in billing charges for the consumption of electric current. It is assumed that various base charges are made according to the size of the consumer. In the present instance, three different base rates are taken to illustrate the 40 mode of operation. The base rate of a particular consumer is indicated on a detail card by the presence of either one of the special perforations x or z or the absence of such perforations. For the present problem, the following schedule of 45 base rates is assumed:

Base 1—3 room house (for a full month) 9 kw. at \$1.10—\$.90.

Base 2—4 room house (for a full month) 12 kw. at \$1.10—\$1.20.

50. Base 3—5 room house (for a full month) 15 kw. at \$1.10—\$1.50.

All other current consumed beyond a minimum amount is to be charged at the following rate:

\$1.10 per kw. h. for first three kw. h. per room, 55 minimum rooms=3.

\$0.05 per kw. h. for next 20 kw. h. per room.

\$0.04 per kw. h. for all other current consumed.

From the above schedule it may be noted that the three different base charges are \$.90, \$1.20 60 and \$1.50. Any additional current consumed will vary the charge according to the base rate.

These various charges are figured in multiplying machines and perforated in the extension cards 10 before they are placed in the reproducer 65 with the related cards 11. They are figured according to the consumption, which is determined by subtracting the last meter reading from the present meter reading indicated on the detail card 11. In the card 11 (Fig. 2) taken as an 70 example, it is seen that the meter readings were 265 and 151 kw., the difference being 114 kw., which is the consumption for which the consumer is to be charged. The corresponding extension card 10 figured for the consumption of 114 kw. 75 bears perforations indicating three different base

charges and three different total charges. Assuming that the special perforation x shown in the card 11 related to a consumer in the class calling for the rate of base 2, the field of the extension card containing perforations relating 5 to base 2 will be sensed when passing through the reproducer and thereby control the perforation of the two fields on the right of the detail card 11. The consumption amount is also perforated in the third field from the right on card 10 11. Before describing how this selective sensing is accomplished, by reference to the wiring diagram of the reproducer, a description of the perforating mechanism is set forth at this point.

15. As cards are fed from the hoppers, an extension card and an associated detail card are placed in related feeding rollers simultaneously and then moved along concurrently and in synchronism, the detail card having an intermittent movement.

20. The extension card passes a sensing station as the detail card passes a punching station. The cards are of the regular Hollerith form and are fed laterally across the short width with the 12 index point leading so that if a special perforation appears at the top of the card, it is sensed at the beginning of the operation to control the punching operation which follows thereafter. The detail cards pause momentarily at each index 25 point position so that if a perforation is to be reproduced, there is time for the punch to penetrate and withdraw from the card between feeding operations.

30. The detail card is drawn under a single line of punches 18, there being one punch for each column of index points on the card, the card moving to bring the various index positions under the punches successively. At the same time that the detail card is passing under the single line of punches 18, the related extension card passes 35 over a single line of sensing brushes 15. Each sensing brush is connected to a magnet to control a related punch. The extension card is sensed at each line of index points and if a perforation appears, a circuit is established through one 40 of the punch control magnets, the armature of which is connected by a call wire to an interposer pawl articulated on the end of a punch plunger. A shoulder on the pawl stands normally out of the path of a positive actuator which is reciprocated as each index point is sensed. If the pawl is selected, it tends to engage the actuator and does so when the actuator is lowered 45 out of engagement with a cam face on the pawl. Another cam face on the pawl cooperates with a 50 stationary bar to hold the pawl in engagement with the actuator as the pawl is moved down and up during the punching and retracting movement.

55. As the detail card 11 (Fig. 1) is fed out of the hopper P by the picker 84, it is engaged by feed rollers 103, 104 and carried to the right. The top of the card then encounters the special brushes 17x and 17z which are alike in construction but differ in being part of separate electric circuits. 60 These brushes may be adjusted along bar 168 to read selected columns which are allotted to carry the special perforations x and z (Fig. 2). With the use of a card design such as that shown in Fig. 2, the brush 17x would be set to read the 65 51st column and brush 17z would be positioned to read the 52nd column. The detail card actuates a card lever DCL as it enters the punching station. The control of the punch by a certain 70 one of a plurality of perforated fields on card 10, 75

as determined by the electrical devices including brushes 17x and 17z, is explained hereinafter with reference to the wiring diagram.

After leaving the special sensing station, the detail card 11 is fed between a punch stripper plate 166 and a die plate 167. This is done at the same time that the related extension card 10 is fed to pass over the sensing brushes 15, so that a selected perforation sensed by a brush 15 may control the depression of a punch 18 to perforate card 11. Card 10 operates card lever RCL2 as it is sensed.

The punch operating means includes a drive shaft 25 which is connected to the operating motor. This shaft is formed with an eccentric 172 which is encircled by an arm 178. The upper end of this arm is pivotally connected to an arm 174 on shaft 175 which is provided with another pair of arms 176.

Between these arms 176 and a punch operating bail 177 there are provided adjustable turnbuckle connections. A threaded rod 178 is pivoted at 179 on arm 176 and another rod 180 is pivoted on bail 177, both rods being connected by a double-ended screw 182 which may be adjusted to varying the position of the bail. The bail 177 is pivoted on studs 183 in the main side frames and carries a punch actuating bar 184 which is adapted to cooperate with notches in any of a plurality of selected interposer pawls 186. Each of the punch plungers 18 is connected to an interposer pawl 186 which is pivotally mounted at the top of the plunger. Normally the pawl is held out of the path of the bar 184 and the plunger is held above the die by a spring attached to the pawls. However, when a sensing brush 15 makes contact through a perforation in an extension card 10, a related magnet PM is energized and the pawl is drawn into cooperation with the bar 184 and the connected plunger is depressed to perforate the detail card 11.

The armature 189 of each punch controlling magnet PM is mounted on a lever 190 pivoted at 191. The lower end of lever 190 is pivotally connected to a call wire 192, the other end of which is connected to pawl 186. A plurality of such connections are made, one to each pawl, the magnets PM being arranged in staggered rows and columns.

When attracted, the armature 189 swings the lever 190 in a counterclockwise direction (Fig. 1) and draws the wire 192 to the right, positioning pawl 186 so that the notch therein comes into cooperation with bar 184. The edge of a stationary bar 196 cooperates with cam faces on pawls 186 to hold the selected pawls into cooperation with bar 184 as the bar is lowered.

An extension on another fixed bar 198 cooperates with the upper ends of the pawls to cam them in a counterclockwise direction out of engagement with the ascending bar 184 on the return stroke of the bail. In order to hold the pawls positively in a disengaged position, the end of bar 184 cooperates with a cam face near the top of each pawl.

The operation of punching is timed to occur during a pause in card feeding when the detail card is not in movement. The eccentric 172 is placed on shaft 25 in such a position that the bail 177 is reciprocated while the driving means for the card feed is out of operation. As the bail and bar 184 are reciprocated, any of the pawls may be moved to the right by the call wires so that the notches in the pawls engage

the end of the bar 184. Then the connected pawls and plungers are depressed to perforate the card and quickly withdraw therefrom to permit the card to be fed to the next index position.

For a more detailed description of the punching devices or any other parts of the machine, reference may be made to the application Serial No. 685,379, filed August 9, 1933, by C. D. Lake, as mentioned hereinbefore.

The wiring diagram

The electrical connections between the devices of the machine may be studied by reference to the wiring diagram shown in Figs. 4A and 4B. When the switch PS is closed, the machine is connected to the source of electrical energy through two main lines 200 and 201.

When the machine is to be used for reproducing, the switches RS1, RS2 and RS3 are set in the "on" position. Detail cards 11 are inserted in the hopper P and extension cards 10 are placed in hopper R. The cards in the hoppers P and R operate the card levers PHL and RHL, respectively, closing contacts PHC and RHC, thus serving to energize magnets M4 and M5. Magnet M5 is connected in line with contacts RHC by connections from bar 203, magnet M5, wire 252, contacts RHC and wire 253 to line 201. When the start key ST is depressed, a circuit may be traced from line 200, wire 206, magnet MRM, wire 207, magnet M1, contacts 11A, contacts STC, lower contacts 4A, lower relay contacts 5A, wire 254, contacts SPC, contacts 14B and wire 211 to line 201. Magnet MRM closes contacts MRC and the motor M is energized. The starting circuit is held through contacts 1A and contacts C3 after the start key is released.

Contacts 1B are closed by magnet M1 and when contacts C1 close, a circuit may be traced from line 201, wire 221, contacts C1, wire 226, contacts 1B, upper contact 2A, wire 217, magnet PCM and line 200. A parallel circuit flows from contacts 1B, wire 219, upper contacts 6A, switch RS1, contacts 11A, reproducing clutch magnet RCM and line 200. Thus both card feed clutch magnets are energized to cause a connection to be made between the driving means and the picker mechanisms and feed rollers associated with both hoppers carrying the record cards. The first extension card in the R hopper and the first detail card in the P hopper are fed to the reproducing sensing station and to the punching die station, respectively.

At the mid-point of this feeding cycle, the extension card operates the card lever RCL1 and the detail card actuates lever DCL, closing contacts RC1 and DC1, respectively, energizing magnets M2, M3, M6, and M7. Magnets M6 and M7 are connected in series with contacts RC1 by wires 255 and 256.

Before the contacts C3 open during the first feeding cycle, another holding circuit is established through contacts operated by magnets M2, M6, M4, and M5. The circuit runs from line 200, through wire 206, magnet MRM, wire 207, magnet M1, contacts 1A, 2B, 4B, 5B, 6B, SPC 14B and wire 211 to line 201. Thereby, the magnets MRM and M1 are maintained energized, the motor continues to run and the card feed clutches connect to the driver until all the cards are fed.

When the cards are feeding in reproducing, the extension card 10 is sensed by brushes 15 in synchronism with the passage of the detail card 11 under the punches 18 controlled by the magnets 75

PM. The magnets are controlled by impulses through the brushes over circuits such as the one running from line 201, Fig. 4B, through the impulse distributor contact C15, wire 259, contacts 5 RC2, closed by lever RCL2, wire 260, contacts R1, closed during a reproducing cycle, common brush 261, contact roller 262, sensing brush 15, socket J2 and a plug wire 326 to socket J4, magnet PM, bus bar 228, and contacts 12B to line 200. Any 10 number of the column sensing sockets may be plugged to any of the punching sockets in this way for the ordinary control of reproduced punching.

For ordinary reproducing perforation, the 15 punch magnets PM are connected directly to the sensing brushes 15 by plug wires such as wire 326, as noted in the foregoing paragraph. According to the present invention, the punch magnets are connected to the sensing brushes through special 20 class selection contacts X1, X2 and Y1, Y2, so that one of three fields of data may be sensed by the brushes and connected to control perforation. These special contacts are controlled by class selection magnets CSX and CSY which in turn 25 are controlled by sensing devices reading the special perforation positions x and z in the detail card 11 (Fig. 2).

When the detail card 11 contains no special 30 perforations, the class selection contacts X1, X2, Y1, Y2 remain in normal position as shown in Fig. 4B. There it is noted that plug wire connections are made from the contacts to three groups of extension card sensing brushes 15. The bottom group of brushes 15 which are normally effective 35 may be assumed to be the ones which read the perforations of base 1 in extension card 10, Fig. 3. They are effective to control reproduced punching by circuits such as the one from line 201, through contacts C15, wire 259, contacts 40 RC2, wire 260, contacts R1, common brush 261, contact roller 262, brush 15 in the lower group of brushes, a plug wire to contacts X2 normally closed, plug connections to contacts Y2 normally closed, plug connections to jack J4, punch magnet 45 PM and contacts 12B to line 200. Thus the punch control magnets are connected to be controlled by the perforations of base 1 on extension card 10, Fig. 3, so that this data is reproduced in the two fields at the extreme right on the detail card 11, Fig. 2.

If a special perforation x (Fig. 2) is sensed in a detail card, the class selection contacts are operated to connect the brushes 15 reading the perforations of card 10 in a field under base 2 55 (Fig. 3) to control the reproduction of the information to be perforated in the section B on card 11 (Fig. 2). The sensing of such an x perforation by brush 11x completes a circuit which may be traced from line 201 (Fig. 4A), through wire 60 319, wires 237, 321, contacts P5, contacts 3A, contact bar 232, brush 11x, closed switch SSX, magnet M8, bus bar 322, and line 200. The energized magnet M8 closes contacts 8A to set up a holding circuit through the magnet, through wire 236 and contacts P2. Associated with the same magnet 65 M8 are contacts 8B which are closed to energize magnet M15. The circuit through M15 may be traced from line 200, through bar 322, magnet M15, wire 317, contacts 8B, contacts C5, wire 258, wire 311, and line 201. The energized magnet M15 operates contacts 16A to provide a sustaining circuit for the magnet and also to set up a sustained current through class selection magnets CSX which are connected in parallel 70

with magnet M15. The holding circuit through magnet M15 includes contacts 15A, wire 316, contacts R3 and wire 320. The other branch of the circuit may be traced through wire 320, contacts R3 wire 316, contacts 15A, plug socket JX, plug 5 wire 324 (Fig. 4B), plug socket JX1, magnets CSX, wire 543 (Fig. 4A) and line 200. Contacts R3 are held closed during the portion of the cycle in which the index points are read on the extension card.

An energized magnet CSX operates to open 10 contacts X2 and close contacts X1, thus connecting the reproducing punch magnets PM to the center group of reading brushes 15 rather than the normally effective lower group of brushes 15. This is true because contacts X1 are connected 15 by plug wiring to socket J2B while contacts X2 are connected to sockets J2A. In this way the special perforation x serves to select the data of base 2 for the control of reproduction.

If a perforation z is sensed on a detail card 11, 20 class selection connections are made to direct the information of the field base 3, on the extension card 10, into the reproduced fields on the detail card. The sensing circuit may be followed on the wiring diagram in Fig. 4A. When the brush 11y is permitted to contact bar 232 through a z perforation, a circuit is formed including line 201, wires 319, 237, 321, contacts P5, closed at the time the special perforation passes the brushes, contacts 3A, bar 232, brush 11y, switch SSY, magnet 30 M9, bar 322, and line 200. The magnet M9 closes its associated contacts 9A to provide a holding circuit through magnet M9. The current continues through magnet M9, contacts 9A, wire 236, contacts P2, wires 237 and 319, to line 35 201. Other contacts 9B are closed by magnet M9. These contacts serve to connect a circuit through magnet M16, wire 318, contacts 9B, contacts C2, and wire 311. The energized magnet M16 closes contacts 16A to sustain the energization of the 40 magnet and also direct current through class selection magnets CSY. The circuit through the magnet flows through contacts 16A, wire 420, wire 316, contacts R3 and wire 320. A circuit through the class selection magnets CSY also includes wire 320, contacts R3, wire 316, wire 420, and contacts 45 16A.

There the circuit branches off through a parallel connection including socket JY, plug wire 323 (Fig. 4B), socket JY1, magnets CSY, wire 543, and line 200. An energized magnet CSY operates 50 the class selection contacts to open contact Y2 and close contacts Y1. Thus, a direct connection is made between the upper group of brushes 15 and the punch magnets PM. An example of such a selected circuit may be traced on the diagram 55 in Fig. 4B. The circuit starts at line 201 and continues through contacts C15, wire 259, contacts RC2, wire 260, contacts R1, brush 261, contact roller 262, brush 15, socket J2C, plug wire to contacts Y1, closed by the operation of magnet CSY, other plug connections from contacts Y1 to socket J4, then through magnet PM, contacts 12B and line 200. Thus, the sensing of a z perforation 60 in the detail card causes the operation of class selection contacts so that sensing devices cooperating with the field of perforations under the heading "base 3" in the extension card 10 of Fig. 3, are connected to control the punching of section B on the detail card 11.

It is noted that another brush 11 (Fig. 4A) is in line with the special brushes 11x, 11y. This brush 65 serves to control operation during gang punching control. When gang punching under control of interspersed master cards, it is necessary to 70 75

suspend operation of the punch during the feeding of a master card. This is accomplished by sensing a special perforation in the master card and completing a circuit through magnets M10 and M11. This circuit is sustained through the closing of contacts 10A so that the magnet M11 may be effective to open contacts 11A to interrupt feeding of cards from the hopper R (Fig. 1) and at the same time, magnet M10 closes contacts 10B to energize the magnet M12.

This magnet M12 is sustained through the closing of associated contacts 12A and when so sustained serves to open the contacts 12B (Fig. 4B) to disconnect the punch magnets PM from operation during the feeding of an interspersed master card.

The control of gang punching is explained more fully in the patent application referred to hereinbefore.

Although the class selection contacts are shown connected in two coordinated groups to select one of three fields of data on a control card, it may be pointed out that either group of contacts such as the pair of contacts X1 and X2 may be used alone to select one of a pair of fields on a control card for the operation of reproducing. Only one set of contacts X1, X2, Y1, Y2 are shown on the diagram, but it is obvious that a plurality of such sets may be used and controlled by the magnets CSX and CSY.

After the operation of punching, it is desirable to check the perforated card with the original information on the extension card. This is done by sensing and comparing the newly perforated data on the detail card in synchronism with the sensing of the original data on the extension card. Turning to Fig. 1, it is noted that after the detail card 11 leaves the punches 18, it is fed to the right over sensing brushes 16. At the same time, the extension cards 16 leave the brushes 15 and run over the brushes 19. A connection is made between the brushes 16 and 19 to detect any dissimilarity between the records. These connections must be class selection controlled so long as the punch selection brushes 16 are class selection controlled because it is desired to check the selected data.

Referring to Fig. 4B, it is noted that class selection contacts Y3, Y4, X3, X4, similar to the class selection contacts already described, are provided between brushes 16 and 19.

The sensing brushes 19, Fig. 1, are not effective for checking until the card lever PCL is operated by a card appearing over the brushes 19. Then the contacts PC1 are closed by lever PCL and a circuit is established through magnet M20, Fig. 4A, contacts PC1, wire 316 and the main lines. This magnet M20 controls the closure of associated contacts 20A, Fig. 4B, which are in series with all the checking brushes 19.

It is noted hereinbefore that when a special perforation x is sensed, the magnet M15 is energized and sustained for operation during punching. This magnet is used in connection with another magnet to sustain the control of class selection for an additional cycle so that the class selection of checking may be accomplished after the card is punched and while it is passing over brushes 19. For this reason, magnet M15 operates to close contacts 15B to complete a circuit through magnet M18. The circuit includes line 201, wire 311, contacts C1, contacts 15B, wire 312, magnet M18, and line 200. Magnet M18 closes contacts 18A to provide a holding circuit including wire 313, contacts P4, and wire 319, to line

201. At the same time, magnet M18 closes another pair of contacts 18B (Fig. 4B). These contacts prepare a circuit through the class selection checking magnets CHX.

The circuit through magnets CHX includes line 200 (Fig. 4A), wire 543, magnet CHX (Fig. 4B), socket J22, plug wire to socket J21, contacts 18B, wire 250 (Fig. 4A), wire 311, to line 201. The checking magnets close contacts XH (Fig. 4B) to provide a holding circuit through wire 251, contacts C6 (Fig. 4A), wire 250, wire 311, and line 201.

The energized class selection magnet CHX operates to open contacts X4 and close contacts X3. This serves to connect the brushes 16 sensing the area under the heading "base 2" on an extension card 18 (Fig. 3) to the brushes 19 cooperating with the reproduced punched area at the right of the detail card 11 (Fig. 2). An example of a checking circuit may be traced on the diagram 20 of Fig. 4B. The circuit includes line 201, contacts C15, wire 259, wire 276, contacts 18A, contacts P5, common brush 280, contact roller 281, brush 16, socket J3B, plug wire to contacts X3, plug wire from X3 to contacts Y4, normally 25 closed, and plug wire from Y4 to socket J6, wire 273, through one coil of check magnet CHM1, to bar 274, contacts 18B, and line 200. The other coil of check magnet CHM1 is connected through wire 275 to socket J6 holding the plug wire 323 30 connected to socket J1 in line with brush 19, contact roller 227, brush 226, contacts P1, wire 225, contacts 20A, contacts C15, and line 201. Thus, the brushes 16 are reading the perforations of base 2 in the extension card at the same time that the brushes 19 are reading the reproduced perforations in card 11. If the perforations agree in location, both coils of checking magnet CHM1 are energized at the same time. Since the polarity is the same on both ends of the core, the 35 magnetizing effects of each coil are neutralized by the current flowing through the other coil and the armature and associated contacts CHC1 of the relay are not closed.

If a perforation in one card does not appear 45 under the checking brushes at the same time as a perforation in the other card, there is an error in punching and only one coil of relay magnet CHM1 is energized. This disturbs the balance of the relay and the associated contacts CHC1 are 50 closed, setting up an indicating circuit. The circuit may be traced from line 201, through wire 311, contact C9, wire 282, contact CHC1, wire 283, magnet M14, magnet M17, and wire 285, to line 200. A lamp L is lighted and continues to give a 55 visible indication of an error as long as magnet M14 is energized. This magnet M14 establishes a holding circuit through operated contacts 14A. A circuit may be traced from line 200, through wire 285, magnets M17 and M14, contacts 14A, wire 286, contacts RC, and wire 287 to line 201. The checking holding circuit may be opened by the operator by depressing the non-check reset key NCR to open the contacts RC.

Turning again to the study of the class selection checking contacts, it is noted that the normal connection through contacts Y4 and contacts X4 connects the lower group of sensing brushes 16 to the checking devices. These connections serve to conduct the normal sensing and checking of the information in the field headed "base 1" on the extension card when no special perforations are sensed in the detail card.

If a special perforation z is sensed in the detail card, the brush 17y (Fig. 4A) is effective to ener- 75

gize magnets M9 and M16. The magnet M16 closes contacts 16B to condition the magnet M19 for checking control. The circuit through magnet M19 includes line 200, bus bar 322, magnet 5 M19, wire 315, contacts 16B, wire 314, contacts C1, wire 311, and line 201. The energized magnet M19 prepares a holding circuit through closed contacts 19A operated thereby. The contacts 19A connect magnet M19 to wire 313, contacts 10 P4 and wire 319.

Referring to Fig. 4B it is seen that magnet M19 closes contacts 19B to condition a circuit through the checking class selection magnets CHY. The circuit through the checking magnets includes 15 wire 543, magnets CHY, socket J20, plug wire to socket J19, contacts 19B, wire 250 (Fig. 4A), wire 311, and line 201. When the magnets CHY (Fig. 4B) are energized, they close associated contacts YH to sustain a circuit therethrough. 20 YH connects the magnets to wire 251 (Fig. 4A) contacts C6, wire 250 and wire 311, to line 201.

The energized magnet CHY opens contacts Y4 and closes contacts Y3 so that the upper group 25 of sensing brushes 16 are connected through the checking devices to the brushes 19. This upper group of sensing brushes 16 cooperates with the group of information under base 3 on the extension card 10 (Fig. 3). This is done so that when 30 information is punched under control of data of base 3, the same punched data is checked with the perforations under base 3. The circuit through the checking magnet CHM1 is similar to the other checking circuit traced hereinbefore, the only exception being that the contacts Y3 make 35 the upper group of sensing brushes 16 effective rather than either of the two lower groups of sensing brushes 16.

When the machine is stopped through the energization of magnet M14 by the checking devices, 40 not only is contact 14B opened to deenergize magnet MRM which in turn opens contacts MRC to stop motor M, but contacts 17A are opened by magnet M17 to prevent restarting until recognition is made of the error in reproducing. Such 45 recognition is made when the non-check reset key NCR is depressed to deenergize magnets M14 and M17 and condition the machine to resume normal reproducing and checking operation.

While there has been disclosed the fundamental novel features of the invention as applied 50 to a single modification, it will be understood that various omissions, substitutions and changes in the form and details of the device illustrated and in its operation may be made by those skilled 55 in the art without departing from the spirit of the invention.

What is claimed is:

1. In a machine for reproducing detail records under control of pattern records, means for sensing a plurality of fields of data on said pattern records, means under control of said sensing means for reproducing data on said detail records, and means under control of the detail records for selecting the fields of data to be reproduced thereon.
2. In a machine for perforating detail records under control of pattern records, means for sensing a plurality of fields of data on said pattern records, means under control of said sensing means for perforating the data of a certain field on the pattern records in said detail records, and means under control of the detail records for selecting the fields of data to be perforated therein.
3. In a machine for producing detail records

under control of perforated pattern records, means for sensing a plurality of separate fields of data perforations in said pattern records, means under control of said sensing means for producing detail records of certain of the perforated 5 data, and means under control of the detail records for selecting the fields of perforations to be sensed in controlling the production of the detail records.

4. In a machine for reproducing a perforated 10 detail record under control of a perforated pattern record, means for sensing a plurality of separate fields of data perforations in the pattern record, means under control of said sensing means for reproducing a certain field of perforations in said detail record, and means under control of the detail record for selecting the field of perforations to be sensed to control reproduction.

5. In a machine for producing a detail record under control of a pattern record, means for sensing a plurality of fields of data on said pattern record, means under control of said sensing means for producing a record of a certain field of data on said detail record, means for sensing a special 15 perforation in said detail record, and means under control of said special sensing means for selecting the field of data to be sensed by the first 20 mentioned sensing means in the production of the record.

6. In a machine controlled by an extension 30 card to perforate a detail card formed with or without one of two special perforations, means for reading three fields of data on the extension card, means for sensing the presence or absence of the special perforations on the detail card, means under control of said sensing means for selecting one of the three fields of data to be read by said reading means, and means under control of the reading means cooperating with the selected field of data for reproducing said data on the detail card. 40

7. In a machine for reproducing data on a record, means for setting up a plurality of fields of data, means under control of the record for selecting a certain field of said data, and means under control of the setting and selecting means for 45 reproducing the selected data on the record.

8. In a machine controlled by a detail card containing one of a plurality of special perforations and an extension record containing a number of fields of data greater than the number of 50 said special perforations, means for sensing the fields of data, means for reading said special perforations, means under control of said sensing means for reproducing data on the extension record on said detail card, and means controlled by the presence of any one of said special perforations or the absence of all of said perforations for 55 selecting one of said fields of data to be sensed for reproducing control.

9. In a machine for checking data on a record with other data, means for setting up a plurality of data, means under control of the record for selecting certain of said data, means under control of the setting and selecting means for comparing the data on the record with the selected data, and means under control of said comparing means for indicating a disagreement in the compared data.

10. In a machine for checking perforations in 70 a detail record with perforations in a pattern, means under control of the detail record for selecting one field of a plurality of fields of perforations in said pattern, means for sensing the selected field of perforations in said pattern, means 75

for comparing the sensed pattern perforations with the detail record perforations, and means under control of said comparing means for indicating a difference in the perforations.

5. 11. In a machine for checking perforations in a detail record with certain of a plurality of fields of perforations in a pattern record, means for sensing a special perforation in the detail record, means under control of said sensing means for selecting one of the fields of perforations in said pattern for reading, means for reading the selected field on said pattern, other means operated in synchronism with said reading means for reading the perforations in the detail record, means under control of both reading means for comparing the perforations, and means under control of said comparing means for manifesting a disagreement in the perforations of the records.
10. 12. In a machine for checking one of three fields of data perforations in a pattern record with the data perforations in a detail record with or without one of two special perforations, means for sensing the special perforations in the detail record, means under control of said sensing means for selecting one of the three fields of data in the pattern for a reading, means for reading the selected field of data perforations in the pattern record, means for reading the data perforations in the detail record, means under control of both reading means for comparing the perforations read, and means under control of said comparing means for stopping the machine when there is a disagreement in the perforations.

15. 13. In a machine for reproducing and checking selected data transferred to a detail record, means for setting up a plurality of data, means under control of the detail record for selecting certain of said data, devices for sensing the selected data, means under control of one of the sensing devices for reproducing the selected data on the detail record, means for reading the data on the detail record after reproduction, means under control of the other of said sensing devices and said reading means for comparing the selected and reproduced data, and means under control of said comparing means for indicating any difference between selected data and reproduced data.

20. 14. In a machine for reproducing and checking a perforated detail card under control of a pattern card having a plurality of fields of perforations, means under control of said detail card for selecting one of said fields, means for sensing the selected field of perforations in said pattern card, means under control of said sensing means for reproducing the selected perforations in said detail card, a second means under control of said selecting means for again sensing the selected field of perforations in said pattern card, means for reading the reproduced perforations in said detail card, means including said second

sensing means and said reading means for comparing the selected and reproduced perforations, and means under control of said comparing means for giving an indication and stopping the machine if there is a disagreement in the perforations.

25. 15. In a machine controlled by a pattern card having a plurality of fields of perforations for reproducing and checking a detail card formed with or without one of a plurality of special perforations, means for sensing the special perforations on the detail card, means under control of said sensing means for selecting one of the fields of perforations in said pattern card, means under control of said selecting means for sensing the selected field of perforations, means under control of the last mentioned sensing means for reproducing the selected perforations in said detail card, a second pattern sensing means under control of said selecting means for again sensing the selected field on said pattern, means for reading the reproduced perforations in the detail card, means under control of said second sensing means and said reading means for comparing the selected pattern perforations and the detail card perforations reproduced therefrom, and means under control of said comparing means for indicating a disagreement between the selected and reproduced perforations.

30. 16. In a machine controlled by perforated records, a magnet controlling an operation of said machine, three electrical controls to which said magnet may be connected selectively, a pair of contacts connected to said magnet, connections from one of the contacts connecting the operating magnet to one of the controls, a second pair of contacts, connections from the other of the first mentioned pair of contacts to said second pair of contacts, connections from the two of the second pair of contacts to the two remaining electrical controls, and a pair of magnets one for each pair of contacts and selectively energized under control of the perforated records to operate one or the other or neither of said pairs of contacts so that a selected one of the three electrical controls is connected to said operating magnet.

35. 17. In a record controlled machine of the class described, means for perforating a record under control of a selected portion of a pattern record, means for comparing the pair of records, means under control of said comparing means for stopping the machine when the selected and reproduced portions of the records do not agree, means for restarting the comparing means, a key for operating said restarting means, another key for reconditioning said comparing means after a disagreement, and means for preventing operation of said restarting means until said reconditioning key is operated.

40. 45. 50. 55. 60. JAMES M. CUNNINGHAM.
